US00D631226S

(12) **United States Design Patent**
Bearson et al.

(10) **Patent No.:** US D631,226 S
(45) **Date of Patent:** ** Jan. 25, 2011

(54) **FOOD PRODUCT**

(75) Inventors: **Kent M. Bearson**, Naperville, IL (US);
William K. Lambrite, Naperville, IL (US);
Garry J. Benedict, Big Rock, IL (US)

D340,118 S 10/1993 Lane
D340,119 S 10/1993 Lane
D340,568 S 10/1993 Lane
D341,469 S 11/1993 Evenson et al.

(73) Assignee: **Sara Lee Corporation**, Downers Grove, IL (US)

(Continued)

(**) Term: **14 Years**

DE 20104984 U 6/2001

(21) Appl. No.: **29/293,713**

(Continued)

(22) Filed: **Dec. 5, 2007**

Assistant Examiner—Barbara Fox

D24/101, 102; 426/78, 87, 89, 94-95, 98, 426/100-101, 103, 104, 129, 138, 139, 144, 426/249, 282-284, 293, 302, 305-307, 400, 426/451, 660, 512, 516-518, 543, 549-550, 426/556, 572, 383, 439, 440, 496, 499, 808; D28/4-6, 8, 1, 8.2; 252/90, 92, 89; D8/393; D32/40

(74) Attorney, Agent, or Firm—Foley & Lardner LLP

See application file for complete search history.

(57) **CLAIM**(56) **References Cited****DESCRIPTION**

U.S. PATENT DOCUMENTS

FIG. 1 is a perspective view of the claimed design;

D29,882 S * 12/1898 Cross D1/129
787,887 A * 4/1905 Baker 426/103
D68,619 S * 11/1925 Epstein D1/127
1,586,528 A 6/1926 Hoddersen-Balling
2,179,672 A * 11/1939 Roys 426/497
2,246,770 A * 6/1941 Wessel 426/87
2,682,471 A * 6/1954 Alther 426/102
2,685,517 A * 8/1954 Dunmire 426/72
D266,030 S * 9/1982 Madonia D1/121
4,525,133 A 6/1985 Bergmann
4,957,271 A 9/1990 Summers et al.
4,984,513 A 1/1991 Choquette
5,005,471 A 4/1991 Dreano
5,009,896 A 4/1991 Becker
D339,898 S 10/1993 Lane

FIG. 2 is a front view of FIG. 1;

FIG. 3 is a top view of FIG. 1;

FIG. 4 is a right side of FIG. 1, the left side being a mirror image of FIG. 4;

FIG. 5 is a bottom view of FIG. 1; and,

FIG. 6 is a rear view of FIG. 1.

The broken lines shown in the drawings are for the purpose of illustrating portions of the food product and form no part of the claimed design.
